(57) **CLAIM**

The ornamental design for an insect eliminating lantern, as shown and described.

DESCRIPTION

FIG. 1 is a top and front perspective view of an insect eliminating lantern showing our new design with a handle in a raised position;

FIG. 2 is a top and rear perspective view thereof;

FIG. 3 is top view thereof;

FIG. 4 is a bottom view thereof;

FIG. 5 is a front view hereof;

FIG. 6 is a rear view thereof;

FIG. 7 is a side view thereof; and

FIG. 8 is an opposite side view thereof;

FIG. 9 is a top and front perspective view of an insect eliminating lantern showing our new design with a handle in a lowered position;

FIG. 10 is a top and rear perspective view thereof;

FIG. 11 is top view thereof;

FIG. 12 is a bottom view thereof;

FIG. 13 is a front view hereof;

FIG. 14 is a rear view thereof;

FIG. 15 is a side view thereof; and

FIG. 16 is an opposite side view thereof;

FIG. 17 is a top and front perspective view of an insect eliminating lantern showing our new design;

FIG. 18 is a top and rear perspective view thereof;

FIG. 19 is top view thereof;

FIG. 20 is a bottom view thereof;

FIG. 21 is a front view hereof;

FIG. 22 is a rear view thereof;

FIG. 23 is a side view thereof; and,

FIG. 24 is an opposite side view thereof.

The broken line showing of portions of the insect eliminating lantern is included for the purpose of illustrating only and forms no part of the claimed design.
